UNITED STATES PATENT OFFICE

162,658

UTILITY TRUCK BODY

James Howard Holan, Rocky River, and Herman J. Troche, Fairview Village, Ohio, assignors to J. H. Holan Corporation, Cleveland, Ohio, a corporation of Ohio

Application October 13, 1948, Serial No. 149,104

Term of patent 14 years

(Cl. D14—3)

To all whom it may concern:

Be it known that we, James Howard Holan and Herman J. Troche, citizens of the United States, said James Howard Holan residing in Rocky River, in the county of Cuyahoga and State of Ohio, and said Herman J. Troche residing in Fairview Village, in the county of Cuyahoga and State of Ohio, have invented a new, original, and ornamental Design for a Utility Truck Body, of which the following is a specification, reference being had to the accompanying drawings, forming part thereof.

In the accompanying drawings:

Figure 1 is a perspective view of the right-hand side of a utility truck body showing our new design, the sliding roof being shown in closed position, and a broken line showing of other truck parts being added for illustration only;

Figure 2 is a left-hand side elevational view;

Figure 3 is a front elevational view;

Figure 4 is a right-hand side elevational view;

Figure 5 is a rear elevational view;

Figure 6 is a rear perspective view of the truck body taken slightly from the left, the scale being enlarged; and

Figure 7 is another perspective view thereof taken from the left and rear, the sliding roof being shown in open position.

We claim:

The ornamental design for a utility truck body, substantially as shown and described.

JAMES HOWARD HOLAN.
HERMAN J. TROCHE.
